UNITED STATES PATENT OFFICE

EDGAR BOURQUIN, OF FRAMINGHAM, MASSACHUSETTS, ASSIGNOR TO WARREN
TELECHRON COMPANY, A CORPORATION OF MAINE

DESIGN FOR A CYCLOMETER CALENDAR CLOCK CASE

Application filed February 9, 1933. Serial No. 47,162. Term of patent 14 years.

To all whom it may concern:

Be it known that I, EDGAR BOURQUIN, a citizen of the United States, residing at Framingham, county of Middlesex, State of Massachusetts, have invented a new, original, and ornamental Design for a Cyclometer Calendar Clock Case, of which the following is a specification, reference being had to the accompanying drawing, forming a part

thereof. The figure is a front perspective view of a cyclometer calendar clock showing my new design.

I claim:

The ornamental design for a container calendar clock case as shown.

In witness whereof, I have hereunto set my hand this third day of February, 1933.

EDGAR BOURQUIN.

CERTIFICATE OF CORRECTION.

Design No. 89,744.

May 2, 1933.

EDGAR BOURQUIN.

It is hereby certified that error appears in the printed specification of the above numbered patent requiring correction as follows: Second column, line 5, for "container cap" read "cyclometer cal-"; and that the said Letters Patent should be read with this correction therein that the same may conform to the record of the case in the Patent Office.

Signed and sealed this 1st day of August, A. D. 1933.

M. J. Moore.
